NEWSPAPER AND MAGAZINE VENDING
MACHINE

Wallace C. Rice, Bridgeton, N. J.

Application March 11, 1938, Serial No. 195,246

5 Claims. (Cl. 312—57)

My invention relates to a machine more especially adapted for vending newspapers and magazines through the operation of a lever operable upon the insertion of a proper coin or coins; that is to say, the machine preferably involves a number of units for newspapers and for different sized magazines, each unit being adapted or adjusted to newspapers, or to magazines, of substantially equal size and salable at the same (a given) price.

One object of the invention is the provision of coin controlled mechanism which may be readily adjusted by the vender to merely receive a coin or coins of a preselected size and which may be easily regulated to move into lever releasing position upon the introduction of a coin or coins of predetermined weight; said mechanism involving a number of regulable coin receiving slots and an adjustable counterpoise whereby the same unit may be readily adapted to different priced newspapers or magazines.

Another object of the invention is the provision of mechanism whereby the newspapers or magazines are forced toward the delivery opening and the foremost newspaper or magazine is separated from the remainder and released through the delivery opening.

The invention also has for its object the provision of a machine which is comparatively simple in construction and positive in operation and at the same time not expensive in manufacture.

The objects and advantages of my invention will all be more readily comprehended from the detailed description of the accompanying drawings, wherein:

Figure 1 is a perspective view of the upper portion of the machine, illustrating a number of superposed units and units arranged in back to back relation.

Figure 2 is a sectional elevation of one unit of the machine with the front wall removed.

Figure 3 is a vertical sectional view taken substantially on the line 3—3 of Figure 2, looking in the direction of the arrows.

Figure 4 is a cross sectional view taken substantially on the line 4—4 of Figure 2, looking downwardly.

Figure 5 is a perspective view of one of the control fingers shown in Figure 4.

Figure 6 is a vertical sectional view taken on the line 6—6 of Figure 2, looking in the direction of the arrows.

Figure 7 is a perspective view, partly in section, of the coin receiving slotways.

Figure 8 is a cross-sectional view of same taken

in the plane of one of the slotways which is positioned to receive a coin.

Figure 9 is a similar view showing the slotway closed.

The machine may consist of a single unit or of any desired number of units as illustrated in Figure 1, with each unit adapted to vend a different sized newspaper and/or magazine and the coin receiving and operating mechanisms adjusted to the required sizes and weights of coins. The mechanisms in each unit are identical and their operations are similar, so that description of a single unit (which constitutes a complete machine) will suffice.

The machine may be made of metal, wood, or any other suitable rigid material, and of cross-sectional configuration suited to the newspapers or magazines to be vended; the respective units 10, in Figure 1, being arranged in superposed and back-to-back relation and each unit preferably provided at the forward end with a hinged lid 11 provided with glass panels; suitable locking means being provided to prevent improper access. The front wall of the unit preferably is arranged at a slope as shown to accommodate the vertically arranged newspapers or magazines—which are arranged with the folded or bound edges downwardly, as shown at A in Figure 3—and also provide for a discharge opening adjacent the front of the casing and controlled by a downwardly opening door 12.

The bottom of the casing is preferably provided with a pair of laterally spaced paper supporting brackets 13, 13 adapted to present smooth and comparatively narrow surfaces to the edges of the newspapers or magazines to eliminate friction and allow the papers to slide readily. The newspapers or magazines, as previously stated, are arranged with the folded or bound edges resting on the slideways or brackets 13; the newspapers or magazines being pressed forwardly through the action of a follower plate 14 which is supported and controlled by a pair of springs 15, 15. The springs 15, 15 are preferably of the long arm type shown in Figure 2 so as to exert substantially equal pressure at all times; one arm of each spring 15 being secured to the rear wall of the casing by suitable brackets as at 16, while the other arm of each spring is secured to the rear face of the follower or pressure plate 14 by suitable brackets as at 17, see Figure 3; the brackets 16 and 17 being such that a wide bearing for the ends of the springs is provided to prevent improper twisting.

Arranged intermediate of the slideways or sup-

55

ports 13, 13 and at the forward side of the casing in proximity to the delivery opening controlled by drop door 12 is the paper controlling mechanism which involves two pairs of fingers 18, 18 and 19, 19, each provided with upstanding ends adapted to be disposed in the path of the forwardly pressed papers. This control mechanism is arranged in a suitable housing 20 disposed transversely of the machine intermediate of the 10 newspaper slide brackets 13, 13. The bottom of the housing 20, or of the main casing, is provided with a supporting plate or bracket 21, provided with upstanding lobes 22, 22, to which fingers 18, 18 are pivotally secured intermediate of their 15 ends as shown at 23, 23 in Figure 4, so as to permit the fingers to rock vertically. The bracket 21 is also provided with an upstanding lobe 24 to which a rocker bar 25 is pivotally secured intermediate of its ends as shown in Figure 4 by 20 bearing 26. The rocker bar 25 is controlled by an arm 28, fixedly secured to the drop door 12; the arm 28 preferably having slot and pin connection with one end of rocker bar 25, see Figure 3. It is apparent from this construction, that when 25 door 12 is swung downwardly, arm 28 will tilt the adjacent end of the rocker bar 25 upwardly and move the opposite end of bar 25 downwardly; the rocker bar 25 tilting about the pin or screw 26.

30 The ends of the horizontally disposed rocker bar 25 are each provided with a pair of laterally disposed spherical extensions 29, see Figure 4, which are adapted to extend into suitable slots or sockets 30, formed at the inner ends of the 35 fingers 18, 18 and 19, 19; the construction of these fingers being substantially identical and more clearly disclosed in Figure 5.

Arranged adjacent the rocker bar 25 and the fingers 18 and 19 are a pair of arcuate adjusting 40 arms or curved members 31, 31 pivotally secured, intermediate of their ends at 32, to the plate or bracket 21, so as to permit these arms to be oscillated in a horizontal direction. The outer ends of these arms 31, 31 are shown provided with a 45 pair of parallel ears 33, spaced to receive the fingers 19, 19 therebetween; the fingers 19, 19 being pivotally secured to the ears 33 at 34 so as to permit the fingers 19 to oscillate in a vertical direction; the arms 31 and fingers 19 being sufficiently spaced to permit the desired oscillation.

The inner ends of the arms 31, 31 are arranged in lapping relation and each provided with a slot as shown in Figure 4 to receive a pin 35 carried by angle plate 36, which in turn is controlled by 50 thumb-screw 37 secured in the rear wall of the housing 20. Upon rotating thumb-screw 37, angle plate 36 is caused to ride lengthwise of the thumb-screw and by reason of pin 35 the arms 31, 31 will both be simultaneously oscillated on their 55 pivot points 32, 32 so as either to move their outer ends (and hence fingers 19, 19) nearer to or farther away from fingers 18, 18, depending on the direction of rotation of the thumb-screw 37. As is apparent from the construction just described, 60 the spacing between the outer upstanding ends of the fingers 18 and 19 may be regulated to the thickness of the newspapers or magazines to be dispensed.

Assuming that the spacing between the fingers 70 18 and 19 as shown in Figure 4 is just sufficient for passage of the usual weekly newspaper, in order to adapt the machine to the bulkier Sunday newspaper, the operator will turn the thumb-screw 37 in the direction which causes angle plate 75 36 to ride toward the end of the thumb-screw 37,

and thereby in turn induce the arms 31, 31 to tilt about their pivots 32, so as to space the tips of fingers 19 farther away from the tips of fingers 18 a distance commensurate with the more bulky paper or magazine.

The upstanding tips of the fingers 18, 18 are substantially coincident with the ends of the paper supporting brackets 13, 13, so that retraction of the finger-tips 18, 18 will allow the foremost paper or magazine to slide off the ends of the brackets 13 and through the delivery opening controlled by downwardly swinging door 12 when the latter has been opened by the mechanism later to be described.

One side of the main casing is shown provided with a vertical partition 38 spaced from the side wall of the main casing to provide a compartment for the coin controlled operating mechanism.

The outer wall of the casing and near the top 20 is provided with a predetermined sized opening or, if desired, slots as shown at 39 in Figures 1 and 6; and secured to the partition 38, or to the main casing coincident with the opening or slots 39, is a cylindrical shell 40 with a segmental cut- 25 out or opening 41 arranged coincident and coextensive with the opening or slots 39 in the casing; the shell 40 being non-rotatably secured in place. Telescopically arranged on the cylindrical shell 40 are a predetermined number of circular bands, 30 as for example shown at 42, 43, 44 and 45; each provided with a slot or cut-away portion 46 of prearranged width and length adapted for insertion of a coin of a given denomination. That is to say, the slot or cut-away portion 46 of band 42, 35 for example, may be of vertical and circumferential dimensions just sufficient to receive a quarter or twenty-five cent piece; the slot 46 of band 43 just sufficient for insertion of a dime; the slot 46 of band 44 just sufficient for insertion 40 of a five cent piece; and the slot 46 of band 45 arranged to receive a one-cent piece. It will be understood, of course, that the number and particular arrangement of the bands may be varied in keeping with the needs and prices of the papers 45 or magazines that are to be dispensed. These bands are intended to be rotated on the inner shell so that the desired slot or slots 46 may be in proper register with the cut-away portion 41, while other slots 46 will be out of register. Each 50 band is provided with a finger piece or binding screw 47 which is adapted to effect binding relation with the inner shell 40 and thereby prevent unauthorized manipulation of the bands; the finger pieces 47 being located within the machine 55 where unauthorized access cannot be had.

The shell 40 is open at the bottom and disposed about the shell is a chute or coin slide-way 48 provided with a downwardly disposed orifice as shown in Figure 6.

Secured to the casing wall and to the partition 38 is a knife-edge fulcrum member 49 (see Figure 6) on which the beam member 50 of a suitable balance mechanism is fulcrumed; the beam 60 50 preferably being in the nature of spaced apart parallel bars in order to prevent sidewise tilting of the beam (see Figure 2); and this beam at one end is provided with a coin receiving pocket 51 provided with a downwardly opening bottom 52 70 pivoted at 53. The bottom 52 is provided with an upstanding side 54 which may constitute one wall of the pocket; and the ends of the bottom forming sheet are bent downwardly to provide a pair of parallelly arranged and spaced apart 75

depending wings 55 provided with a transversely arranged rod or pin 56.

The bottom 52 is held in closed position by a suitable spring 57 secured to the upstanding side 54 and to the beam member 50.

The opposite end of the beam member 50 has a counterweight and latch member 58 pivotally secured thereto.

The beam member 50 is provided with a slideable counterpoise 59 which consists of a metal block of predetermined weight and preferably arranged to straddle and slide on both bars of the beam 50, as shown in Figure 2.

The position of the counterpoise 59 is controlled by the link 60 whose opposite end is pivotally connected with an arm 61 which is fixedly secured to a pin 62 which is disposed through partition 38 and the opposite end of pin 62 provided with a finger 63, shown in dotted lines in Figure 6 and accessible to the vendor from the paper holding compartment of the machine when the main door 11 is opened for the insertion of the papers or magazines.

The partition 38 may be provided with a scale 25 or with a series of holes as at 64 arranged adjacent the tip of finger 63; the scale or arrangement of the holes being provided to aid the vendor in obtaining the correct position of the counterpoise 59 for operation of the balance mechanism when a coin or coins of given weight are inserted through the slot regulating means heretofore described. In order that accidental shifting of the finger 63 may be prevented, the finger may be provided with a small pin adapted 35 to enter the selected hole 64, or other suitable means may be employed.

In order to limit the degree of movement of the beam 50, the partition 38 is provided with a stop pin 65 which prevents the too far upward swing of the coin pocket end of the beam and a second stop pin 66 which prevents the too far upward movement of the counterbalance end of the beam.

Pivotedly mounted on the partition, in the path 45 of the downwardly swinging pocket, is a hook-shaped lever 67, whose one end is pivotally connected to a link 68 which in turn is pivotally connected with a rocker plate 69 which is fixedly secured to a shaft 70 which extends to the exterior of the main casing and is there provided with a pull lever 71, see Figure 2.

The rocker plate 69 is intended to rock or tilt toward the right in Figure 6, and is returned to the normal position shown in Figure 6 by a 55 suitable spring 72.

Adjustably secured to the upper end of rocker plate 69 is an upstanding member 73 which extends into the plane of the lower end of counterbalance member 58 when the balance mechanism has not been provided with coins of the preselected weight determined by the positioning of the counterpoise 59 as heretofore described. With the mechanism in the condition illustrated in Figure 6, it is impossible to operate the pull 65 lever 71 because member 73, secured to rocker plate 69, cannot pass counterbalance member 58; the latter being held against oscillatory movement in one direction by the stop plate 74, secured to the partition 38, and by a stop pin 75 against movement in the other direction.

Pivotedly secured to the forward end of rocker plate 69 is a link 76, whose other end is secured to an upwardly disposed end or flange 77 of the drop door 12 at the delivery opening of the 75 machine.

Any suitable means or receptacle may be provided to receive the coins discharged from the coin pocket 51 of the balance mechanism, as for example shown at 78; and the partition 38 provided with an opening through which the coin 5 receptacle 78 may be withdrawn by an authorized individual.

In practice, the vendor initially regulates the spacing between fingers 18 and 19 in keeping with the thickness of the folded papers to be dispensed 10 and then inserts the uniformly folded newspapers on the slideway or brackets 13, 13 with their folded edges downward, as shown in Figure 3.

With drop door 12 normally in closed position as shown in Figures 3 and 6, the position of fingers 18, 18 and 19, 19 will be as indicated in Figures 2 and 3, namely with the tips of fingers 18, 18 disposed upwardly into the path of the newspapers as shown in Figure 3 and thus hold the papers against further movement to the left 20 in Figure 3 induced by the pressure of the spring controlled follower plate 14.

While the tips of fingers 18, 18 are in the holding position mentioned, the tips of fingers 19, 19 are in retracted or lowered position and in a vertical plane immediately rearward of the rear side of the first newspaper of the lot, as shown in Figure 3.

The vendor at the time of loading the machine also adjusts the coin slots to the size of 30 coin or coins of proper denomination and also adjusts finger or indicator 63 at the point of the scale or designated hole 64 so as to position the counterpoise 59 so that the beam 50 will not tilt until a coin or coins of proper weight 35 have been introduced.

With the paper control fingers 18, 18 and 19, 19, the coin slot bands, and the counterpoise mechanism all adjusted as just stated and the newspapers inserted as described, the machine is 40 in condition for vending and the main door 11, of course, is closed.

Upon insertion of the proper coin or coins, the latter will drop into pocket 51 of the balance mechanism and cause the beam 50 to tilt downwardly where the pin or rod 56 secured to the depending flanges of the pocket-bottom will be in position to be engaged by hook-lever 67 when the purchaser operates pull lever 71. Beam 50 having been tilted as just described, causes 50 counterweight latch member 58 to be raised out of the path of upstanding bar 73, thus enabling the purchaser to operate lever 71. The downward oscillatory movement of lever 71 rotates shaft 70 and causes plate 69 to oscillate with it, 55 thereby opening the delivery door 12, which in turn causes a tilting of rocker bar 25 in such manner that the tips of fingers 18, 18 will be retracted out of contact with the foremost paper and at the same time move the tips of fingers 60 19, 19 upwardly into the path of the second newspaper so as to hold the latter and the succeeding papers against movement toward the discharge opening; the foremost paper at this time having been allowed to drop through the discharge opening at the forward lower side of the machine. Upon releasing lever 71, the mechanism is immediately returned to normal position through the action of the spring 72; at which time door 12 is closed and the fingers 70 18, 19 actuated thereby so that fingers 18, 18 are again in newspaper holding position and fingers 19, 19 in their retracted position.

During the tilting of rocker plate 69—induced by the operator pulling down lever 71—hook 75

member 67 also has been tilted so the hook-end will slightly engage over the pin or rod 56 secured to the depending flanges 55 of the bottom 52 of the coin pocket 51, thereby causing the bottom 52 to be tilted about its pivot 53 allowing the coin or coins to drop down into the receptacle 78. As soon as the coin or coins are released from the pocket 51, the balance mechanism, through the action of the counterweight 10 58, will be returned to normal position; and the pull-lever 71 with the rocker plate 69 and its associated elements, including the delivery door 12, will be returned to normal position through the action of spring 72. The return of 15 the delivery door 12 causes member 25 to be returned to the position shown in Figure 3 where the tips of fingers 18 again will be in position to hold the foremost paper or magazine from movement off of slideways 13, 13 toward 20 the delivery opening, while fingers 19, 19 will be retracted and in position to pass upward between the foremost and next succeeding newspaper or magazine as heretofore described.

It is apparent that my improved machine not 25 only provides for the use of a coin or coins of preselected dimensions through adjustment by the vendor of the coin receiving slots, but also requires the use of a coin or coins of the required gram weight, thus affording adequate production to the vendor; at the same time my improved machine permits ready adjustment to be made by the vendor to adapt the machine to newspapers or magazines of different thickness and selling at a different price.

30 35 I have illustrated what I believe to be a desirable embodiment of my invention which has been described in terms employed for purposes of description and not as terms of limitation, as structural modifications are possible and may 40 be made without, however, departing from the spirit of my invention.

What I claim is:

1. A machine of the character described comprising a casing provided with a newspaper or magazine holding compartment having a discharge opening in the bottom adjacent one end; a closure member for said opening; means whereby the newspapers or magazines are constantly urged toward said opening; means 45 mounted in the casing adjacent the discharge opening and movable into and out of the path of the newspapers or magazines for holding the latter at the opening, a portion of said means being adapted to move into the path of the succeeding newspaper or magazine when the other portion of said means moves out of the path of the foremost newspaper or magazine; means whereby the spacing between the two portions of said last mentioned means may be regulated 50 to the thickness of the newspapers or magazines; spring controlled means, operable from the casing exterior, having link connection with the closure member, whereby the latter is operated and normally held in closed position; and coin 55 controlled latch mechanism tiltably mounted in the casing and normally holding said last mentioned means against operation, said latch mechanism being adapted to tilt out of holding position through the action of an inserted coin.
2. In a machine of the character described, a casing adapted to hold folded newspapers or magazines on edge and provided with a discharge opening in its bottom adjacent the forward end thereof; a closure member for said opening; vertically tiltable members arranged adjacent the

discharge opening in the path of movement of the newspapers or magazines whereby the latter are retarded in their movement toward said opening, said tiltable members being arranged in pairs and the pairs adjustably spaced from each other in the direction of movement of the papers or magazines; lever mechanism adapted to be operated by said closure member and having operative connection with all of said tiltably mounted members whereby one pair of said members is tilted out of the path of the foremost paper or magazine while the other pair of members is tilted into the path of the succeeding paper or newspaper; an externally operable spring controlled lever having link connection at its inner end with the closure member whereby the latter is controlled; and coin controlled latch mechanism whereby the lever is normally held against operation.

3. In a machine of the character described, a chamber adapted to hold newspapers or magazines on edge so as to slide horizontally, said chamber having a delivery opening in its bottom adjacent one end thereof; means whereby the newspapers or magazines are under constant pressure 25 toward said opening; a downwardly opening door for said opening; a plurality of newspaper or magazine controlling fingers tiltably mounted in the bottom of said chamber adjacent said delivery opening, said fingers being arranged in pairs and the pairs arranged in adjustable spaced relation and adapted to alternately tilt into and out of newspaper and magazine holding position when the door is operated; means operatively associated with said fingers and with said door whereby one pair of said fingers is tilted out of holding engagement with the foremost paper or magazine and the other pair of fingers tilted into holding engagement with the succeeding paper or magazine when the door is operated; means whereby the spacing between the pairs of fingers may be adjusted to newspapers or magazines of different thickness; a lever for operating said door; and coin controlled latch mechanism for normally holding the lever against operation.

4. In a machine of the character described, a chamber for holding newspapers or magazines on edge and having a discharge opening in its bottom at one end; means for urging the papers or magazines toward said opening; a door for said opening normally held in closed position; a spring controlled lever, operable from the chamber exterior, having link connection with said door whereby the latter may be opened; a plurality of newspaper or magazine controlling fingers tiltably mounted intermediate of their ends adjacent to said opening, said fingers being arranged in spaced apart groups and the groups being operatively connected with the door whereby to alternately tilt into holding position when the door is operated, the fingers of one group tilting out of holding engagement with the foremost paper or magazine while the second group tilts into holding engagement with the succeeding paper or magazine when the door is operated; regulable means whereby the spacing between the two groups of fingers may be regulated to the thickness of the newspapers or magazines; and coin controlled latch mechanism for normally holding the lever against operation.

5. A machine of the character described, comprising a casing adapted to hold a plurality of newspapers or magazines on edge and having a discharge opening in its bottom; a downwardly

swinging door for said opening; means whereby the newspapers or magazines are constantly urged toward said opening; a plurality of vertically tiltable fingers pivotally mounted intermediate 5 of their ends and arranged adjacent the discharge opening, said fingers being arranged in pairs and the fingers of each pair being disposed in opposite directions, the pairs being spaced apart in the direction of movement of the papers or magazines; a rocker bar operatively connected at its ends with the fingers of the two pairs whereby

the free ends of the fingers of one pair are tilted upwardly while the free ends of the fingers of the other pair are tilted downwardly; means whereby the rocker bar is actuated through movement of the door; a lever operable from the casing exterior and having link connection with said door; and coin controlled latch mechanism whereby the lever and said link mechanism are held against movement. 5

WALLACE C. RICE. 10
